INVENTOR

UNITED STATES PATENT OFFICE.

CHARLES HUNTINGTON JACOBS, OF DETROIT, MICHIGAN.

DESIGN FOR A HOOP.

SPECIFICATION forming part of Design No. 29,039, dated July 12, 1898.

Application filed June 16, 1898. Serial No. 683,661. Term of patent 14 years.

To all whom it may concern:

Be it known that I, CHARLES HUNTINGTON JACOBS, a citizen of the United States, residing at Detroit, in the county of Wayne and State of Michigan, have invented and produced a new and original Design for Hoops, of which the following is a specification, reference being had to the accompanying drawings, forming part thereof.

Figure 1 is a perspective view of a hoop, showing my new design; and Fig. 2 is a detail sectional view.

As shown in the drawings, the leading or material feature of my design consists of a half-round body portion or rib A and a skirt B, disposed and arranged as shown in Fig. 1. The rib A is flat on its inner face and convex on the outer face, thus being in the form of a half-round ring. The skirt B is flat for the

entire width of its inner face and for the greater portion of its outer face. On the lower edge of the outer face the skirt is beveled, as shown at b in Fig. 2.

The entire inner face of the hoop is flat, its outer face being made up of the convex portion of the rib, the flat portion of the skirt, and the beveled portion of the skirt.

Having described my invention, what I claim as new, and desire to secure by Letters Patent, is—

The design for a hoop, as herein shown and described.

In testimony whereof I affix my signature in presence of two witnesses.

CHARLES HUNTINGTON JACOBS.

Witnesses:

JOHN F. BREEN,
ADA J. BLACK.
